FUEL COMPUTING DEVICE

Louis Coplan, Ottawa, Ontario, Canada

Application June 3, 1947, Serial No. 752,061
In Canada May 1, 1947

1 Claim. (Cl. 235—61)

1

This invention relates to a device for making calculations in relation to the consumption of fuel and the like.

The device has a particular application to the oil retailing business and may be particularly adapted to the computation of the rate of consumption of fuel oils and for forecasting when further deliveries to customers will have to be made. Such computations have to be made constantly by distributors of fuel oil, and formerly involved laborious arithmetical operations.

Consumers of fuel oil use the oil at different rates in proportion to the heat loss of the building being heated. The heat loss of a building depends on its size and construction, and varies with the outside temperature. The amount of fuel burned in a given heating plant will therefore vary from day to day with the outside temperature.

These factors, and others, introduce many variables which make the computation of oil deliveries most tedious and require numerous arithmetical calculations. The mathematical work associated with each delivery involves a subtraction, a division, a multiplication and a second division. In view of the large number of deliveries made by each distributor, it is obvious that some errors will inevitably be made. Further, the time involved in making such simple but numerous calculations makes up an appreciable item of cost in clerical work.

The economics of fuel delivery dictate that the largest possible quantity be placed in the consumer's tank on each delivery. That is, it is not economical to make a delivery to a consumer when he has several days' supply on hand. However, a margin of safety must be provided to take care of certain variables. If a consumer runs out of fuel the distributor runs the risk of losing him as a customer.

It is an object of this invention to provide a device by which the distributor can quickly and accurately make all necessary calculations incident to the consumption of fuel so as to plan deliveries at the optimum time, namely that time when the consumer's tank will have only sufficient fuel to provide a margin of safety for variables.

An object of this invention is to provide a device by which fuel computations can be made without any resort to arithmetic or paper calculations.

This invention, a preferred embodiment of which will be described below, presupposes the use of the "Degree-day delivery system" which

2

has been in general use by distributors of fuel oil for some years. The basis of this system is the "Degree-day," usually abbreviated to "DD."

The DD's for a particular day during the heating season is the mean Fahrenheit temperature subtracted from 65. The mean temperature is half the sum of the highest temperature of the day plus the lowest temperature of the day. The "65" represents an assumed room temperature, and some distributors work on an assumed room temperature of 70° in which case the mean temperature will be subtracted from 70.

For example, if the highest temperature during a given day is 48° F. and the lowest temperature during the day is 12° F., then the mean temperature is 30° F. and the number of DD's is 35.

For the purpose of using the Degree-day delivery system, the heating season is usually assumed to begin on the 1st day of September, but 20 may begin earlier. From the first day of the heating season forward the number of DD's for each day is calculated and the result added to the accumulated DD's then existing.

It will be observed that on a colder day more 25 DD's are added to the total of accumulated DD's than on a milder day. For a given heating system the elapsed DD's since the last filling of the tank is an index of the amount of fuel used.

As stated above the rate of consumption in a 30 particular heating plant depends on the heat dissipation which in turn depends on the volume of space to be heated, the construction of the building, the insulation and various other factors. To make the Degree day delivery system adaptable 35 to different heating plants, a factor must be established for each consumer. The factor usually denoted as "K" is defined as the number of DD's which correspond to one gallon of fuel oil in a given heating plant.

40 The factor "K" for a particular heating system is determined by dividing the number of DD's since the last filling by the number of gallons of fuel oil required to re-fill the storage tank, which represent the number of gallons of fuel oil corresponding to the number of DD's accumulated 45 during the period that the stated amount of fuel was used.

Given the elapsed DD's and the number of gallons of fuel oil consumed during this period, the 50 factor "K" is determined. This factor is then multiplied by the optimum delivery in terms of gallonage relative to the amount of storage which forms a part of the installation in the heating plant and this resultant figure is added to the accumulated DD's at the date of delivery. The

next delivery will be made when the accumulated DD's have reached this figure.

For example it will be assumed that a 275 gallon storage tank of a particular installation is filled on October 12th when the accumulated DD's number is 392. The distributor has established a 55 gallon reserve for this tank to take care of variables and the optimum delivery is therefore the remaining capacity of the tank 220 gallons. Based on experience the distributor may set the factor "K" at first conservatively at 4. Multiplying the optimum delivery of 220 gallons by the "K" of 4, the result of 880 is added to the DD's at the last delivery, 392, giving a result of 1,272 DD's. The next delivery will accordingly be made when the DD's reach the total of 1,272. In the year in question it is estimated that the accumulated DD's will reach about this figure on November 18th, which is the date for the distributor to make the next delivery.

When the delivery date arrives, a small discrepancy from the estimate will usually be observed. It will be assumed as an example that on the delivery date the DD's actually reach 1,295 and this particular installation takes 193 gallons. The last filling took place at 392 DD's and this filling at 1,295 DD's results in a difference of 903 DD's, during which time 193 gallons were used. "K" may now be corrected to 4.7 which is again multiplied by 220 gallons and the resultant 1,034 is added to the 1,295 DD's at the date of this last filling forecasting the next filling when the DD's reach 2,329.

This invention provides means for eliminating the above calculations and the accompanying danger of mistakes.

The invention, in its preferred embodiment comprises a base structure having fitted in relation therewith a sliding scale capable of moving in a longitudinal direction and two additional scales longitudinally fixed. One of the said longitudinally fixed scales runs substantially parallel to the sliding scale and the other longitudinally fixed scale is inclined at an angle to the fixed scale in plane of the base. The longitudinally fixed scales have preferably four sides with graduations thereon, and they are rotatable and geared in such a relation together that when one is turned to expose a given side the other is automatically positioned so as to expose a corresponding side. In conjunction with the sliding scale there is preferably a fixed scale which coincides with and corresponds to the sliding scale at one point. Both the sliding scale and its corresponding fixed scale are graduated in degree-days. The four-sided scale disposed parallel to the sliding scale is graduated in gallons and the other four-sided scale disposed at an angle to the sliding scale is graduated to show "K," the number of degree-days corresponding to 1 gallon of fuel. A small transparent ruler is preferably used for reading the results, but other means could be substituted therefor.

A preferred embodiment of this invention will now be described with reference to the drawings.

Figure 1 shows a general plan view of the device as a whole with cut-away portion at three places to show the mechanism more clearly.

Figure 2 shows a front elevation view of the device corresponding to Figure 1.

Figure 3 shows a fragmentary cross-sectional view at either of the indications denoted by III--III in Figure 1.

Figure 4 shows a side elevation view of a por-

tion of the device, and corresponds to Figure 1.

The same numbers denote like parts in all figures.

Referring to Figure 1, the device is shown generally at 1, having a top board 2 and a bottom board 3. The side walls are shown at 4. The sliding scale is shown at 5, graduated in degree-days, and beside it on the top board 2 is fixed degree-day scale 27. The graduations on the DD scales 5 and 27 will be described subsequently.

Gallon scale 6 is rotatably mounted and is disposed parallel to sliding scale 5, and K-scale 7 is likewise rotatably mounted, but is placed at an angle to sliding scale 5. The magnitude of the angle and the graduations on the gallon scale 6 and the K scale 7 will be described later.

As shown in Figure 2, the degree-days scale 5 is cross-shaped in section so that it can be pulled out and inserted in different positions. It is not necessary to have scale 5 rotatable as in the case of gallon scale 6 and K-scale 7, because there is only occasional need to change the position of the degree-days scale. The four sides of degree-days scale cover consecutively the probable elapsed degree-days for any ordinary winter; one side will be used during the early part of the winter and by the time that spring has come the degree-days scale will have been used on its second and third sides and will in all probability have exposed its fourth side. On the other hand scales 6 and 7 are used on their different sides continuously during calculations, since the size of tank and thus also the K factor will vary widely for different customers.

Gallon scale 6 and K-scale 7 are mounted on shafts 11 and 12 respectively, having mounted thereon bevel gears, each of which bevel gears mesh with corresponding bevel gears on a common shaft, so that when the gallon scale 6 is turned so as to expose a scale having a different range, the K scale 7 will rotate to give a different K factor scale suitable for use with the new gallon scale. A knob 17 may be fastened on shaft 11 at the end away from the bevel gear 13 to enable scale 6 to be rotated and simultaneously scale 7 by means of the bevel gear system subsequently described.

In this preferred embodiment, gallon scale 6 is mounted on shaft 11, and shaft 11 is fitted with bearings 22 and 24 to allow rotation but prevent longitudinal motion. Bevel gear 13 is fixed on shaft 11 and is adapted to mesh with bevel gear 18 fixed on shaft 15.

K-scale 7 is similarly mounted on a shaft 12 provided with bearings as at 23 in a manner similar to gallon scale 6. The axis of shaft 12 carrying K-scale 7 is disposed at an angle to degree-day scale 5.

Bevel gear 14 fixed on shaft 12 meshes with bevel gear 19 fixed on shaft 15. Shaft 15 thus provides the connecting linkage between the two scales 6 and 7 and keeps them always in a corresponding relation to each other.

Shaft 15 is shown carried in bearings 20 and 21. Such construction is merely exemplary, and various additions will be obvious to the manufacturer of business machines and the like. Specifically, an interval stop device may be provided, for example by having shaft 15 fitted with four-sided block 8 and by having spring means 9 to hold the shaft in one of the four alternative positions, so that it will not be disturbed by vibration of the board, or the like, but only when knob 17 has applied to it sufficient torque to overcome

the resisting moment inherent in the interval stop device.

Bar 10 is preferably provided to mark the zero position on degree-day scale 27, the advantage of which will be apparent when the operation is described.

A peg or pin may be used with facility in conjunction with scales 5 and 27 for marking a position used in a given set of calculations.

The graduations employed for the various scales will now be described and also the relation which each scale must bear to the others. In describing these scales, "the lower part of the scale" is intended to refer to that part of the scale which is illustrated towards the bottom of Fig. 1, and "the upper part of the scale" to that part of the scale which is illustrated towards the top of Fig. 1. An "ascending scale" designates a scale which shows continuous numerical increments from the lower part of the scale to the upper part of the scale. The gallon scale 6 is an ascending evenly calibrated scale, marked in gallons. A convenient calibration is 10 gallons to the inch, but the calibration chosen depends upon the quantity of oil involved and as has been seen four gallon scales have been provided with different calibrations to provide a wide range to the device. Thus one scale might be calibrated 5 gallons to the inch, a second scale 10 gallons, a third 20 and the fourth 50 gallons to the inch. These scales corresponding to the four sides of the rotating member 6. In each case the lowest quantity marked on the scale is greater than zero. Thus the scale with 10 gallons to the inch might start at 100 gallons and ascend to 250 gallons. An essential point is that the zero points which would result if each of the four scales were extended downwards beyond the confines of the device must coincide. Thus if the lowest calibration of the ten gallon to the inch scale is one hundred gallons, the lowest calibration of the five gallon to the inch scale will be fifty gallons. The reason for this is that otherwise the slope of the K scale 7 could not remain constant and give the desired results. The sliding DD scale 5 is an ascending evenly calibrated scale. Each of the four sides of this scale retains the same calibration interval but covers successive ranges. Thus a convenient calibration would be one side of the scale from 1000 to 4000 at 200 DD's to the inch, one from 4000 to 7000, one from 7000 to 10,000 and one from 10,000 to 13,000. The stationary DD scale 27 is an ascending evenly calibrated scale, with the same calibration interval as that chosen for scale 5. The scale however starts at zero, thus 200 DD's to the inch and 3000 DD's to the scale is adopted for scale 5, scale 27 would run from zero to 3000. The DD scales 5 and 27 are adjacent as the readings should be taken at the dividing line between the two scales for greatest accuracy. It is immaterial, provided the K scale is positioned accordingly, whether scale 27 is placed to the right or left of scale 5. The K scale 7 is positioned so as to make an acute angle with scale 27 as shown in Fig. 1, and so that the zero of the K scale coincides with the zero of the DD scale 27. The angle made by the K scale is such that if the K scale were extended downwards beyond the limits of the device it would intersect the downward extension of the gallon scale at what would be the zero point of the latter if the calibration of the gallon scale were continued along the extension. (Hence is seen the importance of having the zero point of each side of

the gallon scale coincide.) The K scale 7 is an ascending scale but unequally calibrated, the units being spaced increasingly far apart as the scale ascends. The calibrations on this scale can easily be found empirically, the procedure being to choose a point on the gallon scale, say 200 gallons, choose another point on the DD scale 27, say 1400 DD's, divide the DD reading by the gallon scale reading to obtain the K value, in our example K would be seven. Rule through the points chosen on the gallon scale 6 and the DD scale 27 to intersect the K scale 7, and make this point of intersection with the calculated K value, in this case seven. Similarly, the rest of the K scale can be calibrated the fractional number being filled in by interpolation. The distance along the K scale 7 in inches from the zero point of scale 7 for a particular K value may also be calculated using the relationship.

$$\text{Distance along K scale in inches} = \frac{KYD}{X-KY}$$

where

K=the K value the position of which is desired.

25 X=the number of DD's to the inch on scale 27.

Y=the number of gallons to the inch on the gallon scale 6.

D=the distance in inches between the zero point of scales 27 or 7 and the zero point of scale 6 extended.

30 It can be shown by a simple geometric proof involving similar triangles that if the figure chosen on the DD scale 27 is multiplied by a factor, say

$$\frac{3}{2}$$

35 and the same K value is retained, a line drawn through the K value and the new DD reading will intersect the gallon scale at a point which represents the figure chosen on the gallon scale multiplied by the same factor as that applied to the DD scale 27. Thus to continue the example above, retaining the K factor 7 and using a DD reading of 2100, the gallon scale will be intersected at 300.

40 Figures 2 and 4 show elevation views corresponding to the plan view of Figure 1, and since like numbers denote the same parts in all figures, 45 these will be helpful in clarifying the present description.

45 Figure 3 shows a preferred construction of the scales 6 and 7. In this view, the representation is a fragmentary cross-sectional one, taken at either of the designations III-III in Figure 1 the numbers shown in Figure 3 corresponding to III-III on scale 6 in Figure 1. The gallon scale 6 is shown in cross-section, and demonstrates a shape which has been found satisfactory, namely 50 with four flat sides, and routed or grooved with flutes between the flattened sides. This demonstrates the preferred construction for the two rotating scales. The scales 6 and 7 are bored for their entire length to receive shafts 11 and 12, a 55 construction which seems preferable to prevent warping or distortion. To prevent scales 6 and 7 from rotating on shafts 11 and 12, the shafts are provided with tapped transverse holes 28 and the scales are provided with transverse holes 31. 60 Studs 29 threading into shafts 11 and 12 are provided. Other setting means may be used as one skilled in the art will be aware.

65 Top board 2 is provided with slots 25 above scales 6 and 7 considerably wider than one of the 70 flat sides of either scales 6 or 7, so as to permit

free rotation. Frames 26 are countersunk so as to be flush with the upper surface of top board 2, and these frames have a slot therein, the edges of which are shown at 26a, disposed a sufficient distance apart so that only the upward face of the scales are exposed, and yet free rotation is possible.

A typical operation of the device disclosed herein will now be described.

The operator of the device will establish the K value for each customer, which in the absence of breakdowns of the customer's equipment will remain sufficiently constant for practical purposes. He can ascertain this K value for a new customer, after he has made a delivery, by inquiring when this customer last had his tank filled. The operator then looks up in his records the accumulated DD's at the date of last filling. He also computes the accumulated DD's for the present delivery date which will remain constant for all calculations for that day. The operator positions a pin or peg on sliding scale 5 at the point on this scale which represents the DD's at the present delivery date e. g. 4000 and moves the sliding scale 5 until the DD's at the previous filling appear above the bar 10 e. g. 3000. If desired the DD's which have elapsed since last filling can then be read on scale 27. Using the above figures the reading on scale 27 will be 1000. The operator then places a ruler 30 intersecting the DD scale 27 at the DD's which have elapsed since last filling, e. g. 1900 and the gallon scale at the number of gallons which have been delivered to the customer to refill his tanks, say 200. Reading across to the K scale figure five will be obtained for this particular customer, since K is equal to the DD's elapsed divided by the number of gallons required to refill. The peg or pin referred to above can be used to support the ruler. Having obtained the K value for the customer, the optimum gallonage for the customer can easily be calculated since it represents the total capacity of his tank say 250 gallons less his reserve for variables, say 50 gallons. Thus his optimum gallonage will be 200 gallons. This and the K value can conveniently be marked on a card or in a book opposite the name of the customer.

Having obtained the K values and the optimum gallonage figure for each customer, the device can then be used, after a customer's tank has been filled, to make rapid determinations of the DD's which will elapse before the customer's tank requires refilling. This may be accomplished by placing the ruler so that it intersects the K scale at the known value in the example above five, and the gallon scale at the optimum gallonage, e. g. 200. The DD's which will elapse before a delivery is required, in the example 1000 can be read off on scale 27. To convert this to accumulated DD's scale 5 is set so that the accumulated DD's of last delivery, say 4000, appears above the bar 10. The DD reading on scale 5 adjacent to the elapsed DD reading on scale 27 will then represent the accumulated DD's at which delivery should be made. In the example this would be 5000. This may be marked on the customer's card and the cards arranged in order according to the accumulated DD values at which their tanks should be refilled. Thus a glance at the cards will show which customers should have their tanks refilled on a particular day and how much each requires.

The cards will also enable future deliveries to be predicted with some accuracy.

Gallon scale 6 is rotatable so as to provide four scales for various sizes of tanks and therefore various sizes of deliveries. "K" scale 7 rotates in synchronization with gallon scale 6 so as to furnish the correct "K" reading for various sizes of deliveries.

The device which is the subject of this invention, of which the preferred construction has been disclosed represents a substantial advance over previous devices existing in this field, since it enables a complete calculation to be made in about five seconds. The resulting figures are of an accuracy limited only by the closeness with which the scales can be read since the device makes use of exact geometric relationships. This may be contrasted with the approximate figures often produced by this type of device. Its use will result in considerable savings in time to distributors of fuel oil, improved customer relationships and reduced delivery overhead.

What I claim is:

In a device of the character described and including a base supporting structure, a series of scales disposed on the upper surface of the base, and comprising an axially rotatable scale bearing a number of faces, each face being evenly calibrated to represent different ranges, each of which ranges commences at a number greater than zero, a fixed scale in parallel relationship to the rotatable scale, said fixed scale being evenly calibrated from zero, a second rotatable scale capable of rotation in unison with said first mentioned rotatable scale and disposed in angular relationship to the parallel scales, a mechanical linkage connecting said rotatable scales to transmit motion from one scale to the other, the zero point of the angularly disposed rotatable scale and that of the fixed scale coinciding the calibration of the second rotating scale being such that any value on the first mentioned rotating scale and any value on the fixed scale will be in alignment with a value on the second rotating scale which value represents the quotient of the value chosen on the fixed scale divided by the value chosen on the first rotating scale, provided that values are chosen on the first rotating scale and the fixed scale such that a line through them will intersect the second rotating scale, an additional scale capable of longitudinal movement calibrated in identical units to said fixed scale and disposed in the base in a parallel and adjacent relationship to the fixed scale.
